UNITED STATES PATENT OFFICE

2,305,616

SHAFTLESS GYRATORY CONE CRUSHER

Oscar C. Gruender, Milwaukee, Wis., assignor to
 Nordberg Manufacturing Company, Milwaukee,
 Wis., a corporation of Wisconsin

Application August 28, 1940, Serial No. 354,591

15 Claims. (Cl. 83—10)

My invention relates to an improvement in gyratory crushers and has for one purpose the provision of an improved actuating and supporting means for the head of a gyratory crusher.

Another purpose is the provision of a gyratory crusher having a head free from the unitary depending shaft employed prevailingly in previous gyratory crushers and shown, for example, in Patent No. 1,537,565, issued to Edgar B. Symons on May 12, 1925, and reissued on February 16, 1934, as No. 19,154.

Another purpose is the provision of improved supporting means for a gyratory crusher head in which the head is supported and centered by an upstanding portion of the main frame.

Another purpose is the provision of improved oil sealing means for protecting the bearings of the actuating portion of the crusher.

Other purposes will appear from time to time in the course of the specification and claims.

I illustrate my invention more or less diagrammatically in the accompanying drawings wherein:

Fig. 1 is a vertical axial section; and

Fig. 2 is a section on the line 2—2 of Fig. 1.

Like parts are indicated by like symbols throughout the specification and drawings.

Referring to the drawings, 1 indicates any suitable base or foundation, upon which is positioned a circumferentially extending main frame 2, which may for example have a bottom flange 3, resting upon the base 1, and secured to it by any suitable means. The circumferential flange 2 is broken away to provide for an outwardly extending generally cylindrical sleeve 4, the purpose of which will later appear. The flange 2 terminates at its upper edge in an outwardly extending flange 5, having a top face 6, generally horizontal, and an outer generally vertical face 7, an outer inclined face 8, and an inner inclined face 9.

Connected to the main frame by any suitable radial ribs or frame members 10 is a central sleeve 11, one part of which is flattened or reduced as at 12. Mounted on the sleeve 11, and if desired integral with it, is an upstanding cylindrical member 13, having an outer cylindrical surface 14, and a top generally plane surface 15, which may receive a fixed horizon-plate 16. The member 13 is hollow, as at 17, and has a central tube or sleeve 18 secured to it by any suitable generally radial connecting members 19. The tube may receive or form an oil line 20, in line with the top aperture 21 of the plate 15 and may receive at its bottom end any

suitable connecting member 22, communicating with the oil line 23, extending from any suitable pump or source of lubricant. A ledge 24 connects the sleeves 11 and 13, and is provided with supporting means or rings 25, as shown in Fig. 1. The upper edge of the sleeve 11 terminates in an enlargement 26, preferably having an upwardly and inwardly inclined surface 27, and an inner generally cylindrical surface 28, which may be provided with channels 29 to receive sealing rings 30.

Rotatable about the member 13 is an eccentrically apertured sleeve 31, having an inner cylindrical bearing 32 and an outer cylindrical bearing 33. The axes of these two bearings are inclined in relation to each other. At the bottom of the sleeve 31 is a gear 34, which may be keyed or otherwise secured thereto, and is in mesh with the pinion 35 on the drive shaft 36 in the bearing sleeve 37, having a bearing or bearings 38, located in the sleeve 4 in the main frame. The sleeve 37 has an enlargement 40, which closes an aperture in the sleeve 11, as shown in Fig. 1. The space between the enlargement 40 and the flattened portion 12 serves as a housing or space for the pinion 35.

Mounted for sliding movement on the top bearing plate 16 is a crusher head supporting plate 41, having a bottom plane surface 42, conforming to the upper surface of the plate 16, and a top spherical concave bearing surface 43, the sphere of which is described about the center A, located above the crushing cavity. The center A is located by the intersection of the axes A—B and A—C. A—B is the central axis of the outer periphery of the fixed upstanding cylindrical member 13 and A—C is the central axis of the outer periphery of the eccentrically apertured sleeve 31. The plate 41 is provided with an oil passing aperture 44, generally aligned with the oil passages 20 and 21. It will be understood that the relative movement of the members 41 and 16 is slight, but a perceptible amount of lateral movement is advantageous.

50 55 50 generally indicates a crushing head having a central downwardly convex spherical bearing surface 51, which seats upon and conforms to the upper surface 43 of the plate 41. 52 indicates the generally conic body of the head, from which depends a generally cylindrical sleeve 53, which engages and conforms to the bearing 33 of the sleeve 31. It is preferably provided intermediate its top and bottom with a downwardly and outwardly inclined apron 54. Interposed between the outer surface of the lower

portion of the sleeve 53 and the flange 26 is a sealing ring 55, which may be secured to the gear 34 as by any suitable bolt or bolts 56, and rotates in unison with the gear 34. The sealing ring 55 has an inner enlargement 57, with an upward conic extension 58, extending beneath the shield 54. The body portion 57 is provided with channels 59 to receive sealing rings 60, which seal between the ring portion 57 and the exterior of the lower portion of the sleeve 53 of the head. The ring 55 also has an outer cylindrical portion 61 opposed to the sealing rings 30 on the frame flange 26, and an outer apron 62, which extends downwardly about the conic surface 27 of the flange 26. Thus the ring is effective as a sealing connection between the frame portion 11, and the head sleeve 53, and the overhanging aprons 54 and 62 are an additional protection against the penetration of dust into the bearings. The lower edge of the head may also be provided with a downwardly extending protecting apron 65, which is a further protection against dust.

The head is shown as provided with an upwardly extending sleeve 66, screw threaded at the top, as at 67, to receive any suitable locking nut 68, which exerts a downward thrust on a conic compression member 69, the lower edge of which engages the upper edge of any suitable conic crushing mantle 70, which rests on the outer conic surface of the head 52.

71 indicates any suitable packing of zinc or the like. 73 is any suitable feed restricting or feed distributing plate, mounted above the nut 68. Since the details of the feed plate and its connection to the head do not of themselves form part of the present invention, they are not described or shown.

Mounted upon the flange 5 is a ring 80, having a downward circumferential channel 81, defined by surfaces corresponding to the surfaces of the flange 5. Any particular upwardly converging conic surfaces 82 and 82a are provided, which engage the corresponding surfaces 8 and 9 of the flange 5. The ring 80 is normally held clamped downwardly against the flange 5 by any suitable means, including for example tension members or bolts 83, having at their lower ends an abutment ring 84. A plurality of coil springs 85 serve to thrust the ring 84 downwardly, the coil springs being compressed between the ring 84 and the lower face of the flange 5. They are purposely so set that when uncrushable material, tramp iron or the like, passes through the crushing cavity, the ring 80 may lift slightly. The ring 80 carries a screw threaded annular portion 86, which receives in screw threaded relation the bowl structure, including an outer cylindrical portion 87, to which is secured, or with which is integrally formed, an inner conic bowl 88, which receives the crushing bowl liner 89, which may be secured in position for example by hook-shaped lugs 90, which extend through apertures 91 in the bowl 88, and are held by U-bolts 92, located in the space between the bowl portions 87 and 88.

The top of the bowl portion may be closed by any suitable upwardly and outwardly conic shield 93, which may be provided with wear plates 94. 95 is an additional exterior shield, and 96 a generally cylindrical feed directing member. It will be understood that the bowl structure in general may be adjusted as to height in relation to the ring by imparting relative rotation to the members 87 and 95. However, since the details of this adjustment do not of them-

selves form part of the present invention, they will not be herein described.

It will be understood that oil may be delivered in any suitable manner along the line 23 and upwardly along the line 20 to the bearings 42 and 43, whence it may pass outwardly and lubricate the bearings 32 and 33. Oil may also pass by the passage 97 to the bearing 38.

It will be realized that, whereas I have described and illustrated a practical and operative device, nevertheless many changes may be made in the size, shape, number and disposition of parts without departing from the spirit or my invention. I therefore wish my description and drawings to be taken as in a broad sense illustrative or diagrammatic, rather than as limiting me to my precise showing.

The use and operation of my invention are as follows:

The mantle 70 and the liner 89 define a crushing cavity, into which material is delivered from above, and where it is crushed by the gyration of the head about the center A. The movement of the head is defined by the opposed bearing surfaces 43 and 51, and is a gyroscopic movement about the center A, in which the zone or point of approach of the head to the bowl passes circumferentially about the crushing cavity in regular sequence.

30 The head is gyrated in response to the rotation of the eccentrically apertured sleeve 31. Since the movement of the head is circular and not a movement of translation, the axes of the bearings 32 and 33 are inclined in relation to each other.

35 A rotation of the shaft 36 by any suitable motive means causes a unitary rotation of the gear 34 and the eccentrically apertured sleeve 31. The thick side of the sleeve 31 is thereby moved circumferentially about the central fixed frame members 13, and the result is the desired gyration of the head and its consequent crushing action.

40 The sealing member 55 moves in unison with the gear 34, and the thin side of the sealing ring 55 is thereby always aligned with the thick side of the sleeve 31.

45 The downwardly extending sleeve 53 of the head receives the thrust of the exterior bearing 33 of the eccentrically apertured sleeve 31. The sealing ring is effective to seal both against the exterior of the sleeve 53 and the interior of the flange 26, thus providing an effective seal against the penetration of dust or grit into the bearings. The overhanging aprons 54 and 62 are further advantageous in preventing the access of dust to the bearings.

50 I claim:

55 1. In a gyroscopic crusher, a main frame, a generally central member upstanding from said main frame and having a generally cylindrical exterior bearing surface, an eccentrically apertured sleeve mounted on and rotatable about said upstanding member, and means for rotating it, said sleeve having inner and outer generally cylindrical bearing surfaces, the axes of said bearing surfaces being at an angle to each other, said upstanding member having a generally flat upper bearing surface, a bearing plate mounted upon said bearing surface and having a bottom flat bearing surface opposed to said bearing surface, and a top spherical upwardly concave bearing surface, a crushing head having a downwardly convex spherical bearing surface seated on and conforming to the upwardly concave bearing surface of said plate, and a downwardly extending cylind-

drical member having an inner bearing surface conforming to the exterior bearing surface of said eccentrically apertured sleeve, and a crushing bowl surrounding said crushing head and defining with it a crushing cavity.

2. In supporting and actuating means for the head of a gyratory crusher, an upstanding supporting element having a generally cylindrical exterior side bearing surface and a generally plane generally horizontal top bearing surface, a bearing plate mounted on said top bearing surface and having a bottom plane face opposed to said top bearing surface, and an upwardly concave spherical top bearing face, an eccentrically apertured sleeve surrounding said exterior cylindrical bearing surface, and means for rotating it, said sleeve having exterior and interior generally cylindrical bearing surfaces, the axes of which are inclined to each other, and a head having a downwardly convex spherical bearing surface conforming to the spherical concave bearing surface of said plate, and an inwardly cylindrical bearing surface surrounding and conforming to the exterior bearing surface of said eccentrically apertured sleeve.

3. In supporting and actuating means for the head of a gyratory crusher, an upstanding supporting element having a generally cylindrical exterior side bearing surface, a bearing member mounted at the top of said element and having an upwardly concave spherical top bearing face, an eccentrically apertured sleeve surrounding said exterior bearing surface, and means for rotating it, said sleeve having exterior and interior generally cylindrical bearing surfaces, the axes of which are inclined to each other, and a head having a downwardly convex spherical bearing surface conforming to said upwardly concave spherical bearing surface, and an inwardly cylindrical bearing surface surrounding and conforming to the exterior bearing surface of said eccentrically apertured sleeve.

4. In supporting and actuating means for the head of a gyratory crusher, an upstanding supporting element having a generally cylindrical exterior side bearing surface, a bearing member mounted at the top of said element and having an upwardly concave spherical top bearing face, an eccentrically apertured sleeve surrounding said exterior bearing surface, said sleeve having exterior and interior generally cylindrical bearing surfaces, the axes of which are inclined to each other, and a head having a downwardly convex spherical bearing surface conforming to said upwardly concave spherical bearing surface, and having a lower and downwardly extending sleeve having an inwardly cylindrical bearing surface surrounding and conforming to the exterior bearing surface of the eccentrically apertured sleeve.

5. In a gyratory crusher, a crusher frame, an upstanding element on said frame having a generally cylindrical generally vertical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, and a head having a bearing surface surrounding and conforming to the exterior bearing surface of the eccentric sleeve, and supporting means for said head, including an upwardly concave spherical bearing element supported by the frame, and a downwardly convex spherical bearing element conforming thereto and associated with the head.

6. In a gyratory crusher, a crusher frame, an upstanding element on said frame having a generally cylindrical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, the axis of the inner surface and the exterior side bearing surface of the upstanding element being generally vertical, and a head extending about an upper portion of said upstanding element and having a bearing surface surrounding and conforming to the exterior bearing surface of the eccentric sleeve, and means for supporting said head, including a direct supporting connection between said head and a fixed portion of said frame.

7. In a gyratory crusher, a crusher frame, an upstanding element on said frame having a generally cylindrical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, the axis of the inner surface and the exterior side bearing surface of the upstanding element being generally vertical, and a head extending about an upper portion of said upstanding element and having a bearing surface surrounding and conforming to the exterior bearing surface of the eccentric sleeve, and means for supporting said head, including an upwardly concave spherical bearing surface associated with the head, and a downwardly convex spherical bearing surface supported by the frame and adapted to receive the downwardly convex spherical bearing surface of the head.

8. In a gyratory crusher, a main frame, an upstanding element on said main frame having a generally cylindrical generally vertical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, and a head having a bearing surface surrounding and conforming to the exterior bearing surface of the eccentric sleeve, said upstanding element having an upwardly concave spherical bearing surface adapted to support said head, said crushing head having a downwardly convex spherical bearing surface resting on and conforming thereto.

9. As a new article of manufacture, a crusher head having a generally conic body portion having an outer crushing face and a generally centrally located downwardly convex spherical bearing surface, and a sleeve downwardly extending from the bottom of the head, said sleeve having an internal generally cylindrical bearing surface of a length of the general order of the height of the crushing face of said body portion, and a generally conic eaves element extending downwardly and outwardly from the outer face of said sleeve intermediate top and bottom thereof.

10. As a new article of manufacture, a crusher head having a generally conic body portion having an outer crushing face and a generally centrally located downwardly convex spherical bearing surface, and a sleeve downwardly extending from the bottom of the head to a level substantially below the lower end of the crushing face, said sleeve having an internal generally cylindri-

cal bearing surface of a length of the general order of the height of the crushing face of said body portion, and extending circumferentially about said spherical bearing surface, said spherical bearing surface being located adjacent the level of the upper end of the sleeve, and a generally conic eaves element extending downwardly and outwardly from the outer face of said sleeve intermediate top and bottom thereof.

11. As a new article of manufacture, a crusher head having a generally conic body portion having an outer crushing face and a generally centrally located downwardly convex spherical bearing surface extending continuously across the central portion of the head, and a bearing sleeve extending downwardly below said convex spherical bearing surface, said sleeve having an internal bearing surface.

12. As a new article of manufacture, a crusher head having a generally conic body portion having an outer crushing face and a generally centrally located downwardly convex spherical bearing surface extending continuously across the central portion of the head, and a bearing sleeve extending downwardly below said convex spherical bearing surface, said sleeve having an internal bearing surface, of a length of the general order of the height of the crushing face of said body portion.

13. As a new article of manufacture, a crusher head having a generally conic body portion having an outer crushing face and a generally centrally located downwardly convex spherical bearing surface extending continuously across the central portion of the head, and a bearing sleeve extending downwardly below said convex spherical bearing surface, said sleeve having an internal bearing surface, said spherical bearing surface being located adjacent the level of the upper end of the sleeve.

14. In a gyratory crusher, a crusher frame, an

upstanding element on said frame having a generally cylindrical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, the axis of the inner surface and the exterior side bearing surface of the upstanding element being generally vertical, and a head extending about an upper portion of said upstanding element and having a bearing surface surrounding and conforming to the exterior bearing surface of the eccentric sleeve, and means for supporting said head, adapted to permit said head to gyrate about a center coincident with the intersection of said axes, said center being located adjacent an upper part of the head.

15. In a gyratory crusher, a crusher frame, an upstanding element on said frame having a generally cylindrical exterior side bearing surface, an eccentrically apertured sleeve surrounding and conforming to said exterior bearing surface, and means for rotating it, said sleeve having exterior and interior generally cylindrical bearing surfaces, the axes of which are inclined to each other, the axis of the inner surface and the exterior side bearing surface of the upstanding element being generally vertical, and a head extending about an upper portion of said upstanding element and having a bearing surface surrounding and conforming to the exterior bearing surface of the eccentric sleeve, and means for supporting said head, including a direct supporting connection between a portion of the head and the upstanding element, adapted to permit said head to gyrate about a center coincident with the intersection of said axes, said center being located adjacent an upper part of the head.
